UNITED STATES PATENT OFFICE

MICHAEL M. CLARK AND PETER MCKERNAN, OF SHENANDOAH, PENN-SYLVANIA.

OVERSHOE.

SPECIFICATION forming part of Letters Patent No. 371,738, dated October 18, 1887.

Application filed June 29, 1887. Serial No. 242,879. (No model.)

To all whom it may concern:

Be it known that we, MICHAEL M. CLARK and PETER MCKERNAN, both of Shenandoah, in the county of Schuylkill and State of Pennsylvania, have invented new and useful Improvements in Overshoes, of which the following is a full, clear, and exact description.

Reference is to be had to the accompanying drawings, forming a part of this specification, in which similar letters of reference indicate corresponding parts in all the figures.

Figure 1 is a perspective view of our new and improved overshoe. Fig. 2 is a bottom view of the same; and Fig. 3 is a sectional elevation taken on the line $x-x$ of Fig. 2.

The invention will first be described in connection with the drawings, and then pointed out in the claim.

The bottom A of the shoe is made of sheet metal stamped up in a die to form the flange B and the hollow heel C.

To the flange B is secured by rivets $a-a$ the upper D of leather or other material, and to the upper edge of the heel-flange C' is secured the heel-piece or counter E of leather or other material.

The bottom A is corrugated, as shown at a' ,

and formed with points a^2 to prevent slipping, and the bottom of the heel is also formed with points a^3 to prevent slipping. The bottom A 30 may be re-enforced by a separate sole, F, of sheet metal, and in this are formed points e to prevent slipping.

The overshoe may be fastened on by buckle-straps G, or the upper D may be slitted and 35 eyeleted, as shown at f , to receive lacing-strings for fastening the shoe upon the foot.

Having thus fully described our invention, we claim as new and desire to secure by Letters Patent—

As a new and improved article of manufacture, an overshoe composed of the stamped sheet-metal bottom A, formed with the flange B, and the stamped sheet-metal heel C, in combination with the metal top sole, F, leather 45 upper D, and heel or counter E, secured to the flange B and upper edge of the metal heel, substantially as described.

MICHAEL M. CLARK.
PETER MCKERNAN.
